US00D895638S

(12) **United States Design Patent** (10) **Patent No.:** **US D895,638 S**
van den Berg et al. (45) **Date of Patent:** ** *Sep. 8, 2020

(54) **DISPLAY SCREEN OR PORTION THEREOF WITH GRAPHICAL USER INTERFACE**

(71) Applicant: **Sonos, Inc.**, Santa Barbara, CA (US)

(72) Inventors: **Liesbeth van den Berg**, Medford, MA (US); **Abhishek Kumar**, Santa Barbara, CA (US); **Eduardo Apodaca**, Santa Barbara, CA (US); **Amber Braden**, Santa Barbara, CA (US); **Mark Trammell**, Santa Barbara, CA (US); **Robert Lamourne**, Santa Barbara, CA (US); **Yasser Rashid**, Amersterdam (NL)

(73) Assignee: **Sonos, Inc.**, Santa Barbara, CA (US)

(*) Notice: This patent is subject to a terminal disclaimer.

(**) Term: **15 Years**

(21) Appl. No.: **29/586,073**

(22) Filed: **Nov. 30, 2016**

Related U.S. Application Data

(63) Continuation of application No. 29/484,344, filed on Mar. 7, 2014, now Pat. No. Des. 775,632.

CLAIM

The ornamental design for a display screen or a portion thereof with graphical user interface, as shown and described.

DESCRIPTION

The FIGURE is a front view of a display screen or portion thereof with graphical user interface showing our new design.

The dot-dash broken line showing a display screens or portion thereof, and the other broken lines showing elements of the graphical user interface illustrate portions of the article, none of which form part of the claimed design.
